(57) **CLAIM**

The ornamental design for a remote control, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a remote control showing our new design;

FIG. 2 is a front view thereof; and,

FIG. 3 is an enlarged view of FIG. 2 with disclaimed environment removed for clarity purposes.

The dash-dot-dash style broken line immediately adjacent to the shaded area defines a peripheral bound of the claimed design and forms no part thereof. The even-length broken lines represent aspects of the remote control that form no part of the claimed design.
